UNITED STATES PATENT OFFICE.

ARTHUR RICHMOND, OF LEEDS, ENGLAND, ASSIGNOR TO HENRY RICHMOND & SONS
LIMITED, OF LEEDS, ENGLAND.

DESIGN FOR AN IRON BOOT PROTECTOR OR STUD.

54,678.

Specification for Design.

Patented Mar. 9, 1920.

Application filed August 13, 1919. Serial No. 317,358. Term of patent 14 years.

To all whom it may concern:

Be it known that I, ARTHUR RICHMOND, a subject of the King of Great Britain, residing at Leeds, in the county of York, England, have invented a new, original, and ornamental Design for an Iron Boot Protector or Stud, of which the following is a specification, reference being had to the accompanying drawing, forming part thereof.

The figure is a perspective view of an iron boot protector or stud constructed in accordance with my invention; and the novelty in

the design consists in the shape or configuration of the three-unit integral stud, as shown.

What I claim as my invention and desire to secure by Letters Patent is:—

The ornamental design for an iron boot protector or stud, as shown and described.

ARTHUR RICHMOND.
